UNITED STATES PATENT OFFICE.

HORACE H. BURDETT, OF HOPEDALE, MASSACHUSETTS, ASSIGNOR TO DRAPER CORPORATION, OF HOPEDALE, MASSACHUSETTS, A CORPORATION OF MAINE.

BUILDER MECHANISM.

Application filed May 21, 1925. Serial No. 31,931.

To all whom it may concern:

Be it known that I, HORACE H. BURDETT, a citizen of the United States, and a resident of Hopedale, in the county of Worcester and State of Massachusetts, have invented an Improvement in Builder Mechanisms, of which the following description, in connection with the accompanying drawings, is a specification, like characters on the drawings representing like parts.

This invention relates to builder mechanisms for yarn winding or spinning machines, and more particularly to such mechanisms provided with a bunch building attachment.

In that type of looms known as "feeler" looms, it is now the common practice to wind filling carriers or bobbins for use in such looms by providing a few preliminary windings upon the filling carriers or bobbins, technically known as a "bunch" and upon the completion of such preliminary winds or bunch to pass to regular service windings, and various types of mechanisms have been devised for this purpose. One of the objects of the present invention is to provide a builder mechanism with a bunch builder attachment of simple and novel character, which is readily applicable to builder mechanisms now in common use.

As ordinarily practiced, the yarn guide, or ring rail it may be, is depressed on the completion of a series of wound bobbins to permit the full bobbins to be doffed, and such yarn guides or ring rail are usually held in such lowered position by some sort of a catch or trip.

When a series of filled bobbins have been replaced by empty bobbins or filling carriers and a bunch is to be placed upon the filling carriers or bobbins, it is desirable that the bunch building mechanism may be placed in operative position to wind the bunch when the machine is again started, and one of the purposes of the present invention is to provide a bunch building attachment which will enable the machine attendant to place the bunch building mechanism in operative relation before starting the machine

to wind a fresh set of bobbins, and which will thereafter and on completion of the bunch automatically pass to regular traverse which will continue to the end of the winding operation.

In accordance with the present invention, the bunch building attachment comprises a worm having spiral threads, and which is mounted upon the builder arm for movement transversely thereto and is normally quiescent during regular windings, and in addition thereto the invention provides a rotating device for engagement with the threads of the worm to progressively move the worm from operative relation with said device on the completion of the bunch, to thereby permit continuation of the windings by regular traverse. To move the bunch builder mechanism into operative relation to build the bunch, the worm on the builder arm is manually controlled to move it into bunch building position prior to the commencement of the windings of the new set of bobbins, and the direct engagement of the rotating bunch building device with the worm threads serves to maintain the worm in bunch building relation with said device and to be automatically rotated thereby to move the worm into its inoperative position.

The invention, novel features thereof and new combination of parts will best be made clear from the following description and the accompanying drawings of one good practical form of the invention, which in its true scope will be definitely set forth in the claims.

In the drawings:

Fig. 1 is a perspective view of a winding machine and builder mechanism containing the present invention;

Fig. 2 is an enlarged side elevation showing more particularly the builder mechanism and bunch builder attachment in their operative relation during the building of a bunch;

Fig. 3 is a transverse section on the line 3-3 of Fig. 2 but showing the relation of parts during regular traverse.

The advantages of the present invention

are well manifested in connection with a spinning machine, and as shown in the present instance, the spinning machine is of the "ring" type, but obviously the invention is not restricted thereto, as it may be advantageously employed in connection with any machine for winding bobbins with filling wind.

The spinning or winding machine may be of any usual character, and as shown in Fig. 1 it may comprise the usual frame 1 having the spindle rail 2 on which the spindles 3 are mounted for rotative movement. Above the spindle rail 2 is shown the usual

ring rail 4 having the yarn guides or rings and travelers 5 for directing the yarn to the bobbins during the traverse of the ring rail.

Mounted in suitable brackets 6 extending from the cross-tie 7 is the rock shaft 8 having an arm 9 on which rests the rods 10 connected to the ring rail and normally tending to be raised by the counter-weight 11, as usual. The rock shaft 8 has the segment arm 12 to which may be connected the flexible connection or chain 13 which passes over the guide pulley 14 and has its lower end portion secured to the let-back drum 15 mounted on the builder arm 16. The builder arm 16 is pivotally mounted upon the machine frame as at 17 and has a rearwardly extending arm on which is supported a weight 18. The builder arm 16 has a follower 19 which during the main traverse windings rests upon the periphery 55 of the main builder cam 20 which may be appropriately supported on the rotative shaft 21 driven, as usual, from some going part of the machine. These parts may be of usual construction.

Mounted upon the builder arm is the usual pick shaft 22 to which is secured the pick wheel 23 by which the pick shaft is stepped along or rotated, as usual in this type of builder mechanism, during the rising and falling movement of the builder arm under the actuation of the main builder cam. Secured to the pick shaft 22 is a worm 24 which engages a toothed wheel 25 to which the let-back drum 15 is secured, so that during the main service windings the ring rail will be progressively raised to lay the main service windings in usual manner. All the parts so far described may be of usual construction and need no further elucidation, since they are well known in the art.

The builder arm 16 as shown has adjustable secured thereto by the bolts 26 a bracket 27, and adjusting screws 28 form a convenient means for adjusting the bracket relative to the builder arm when the bolts 26 are loosened for this purpose.

A stud or dead shaft 30 is adjustably mounted in the lower portion 29 of the bracket 27 by threaded connection therewith, as shown in Fig. 3, and is provided

with a check nut 31 for holding the stud in adjusted position. The stud is enlarged at its outer portion to form a stop shoulder 30^x and mounted for sliding movement on the enlarged outer portion of the stud 30 is a worm 32 having a sleeve or hub portion 33, the inwardly extending edge 33^x of which engages the shoulder 30^x when the worm is moved outwardly from the builder arm into bunch building position.

Mounted for rotative movement is a bunch building device 34 which is shown in the present instance as mounted upon the cam shaft 21 and may be conveniently secured thereto for rotative movement therewith by means of the bolts 35, the construction being such that when the builder arm 16 is lowered by the machine attendant, he may move the worm in a direction transversely of the builder arm by manual effort into position below the rotating bunch builder device 34, which will thereupon engage the threads of the worm and maintain the parts in operative relation to progressively move the worm transversely of the builder arm out of operative relation when the bunch has been completed, whereupon regular service traverse ensues.

The rotating bunch building device 34 is herein shown as of the general disk form, but the invention is not necessarily limited in this respect, and if desired its periphery may be varied in form. In order, however, to properly retain the worm 32 and rotating bunch building device 34 in operative relation when they are directly engaged to build the bunch, the edge portion 36 is formed to register with the threads of the worm, the construction being such that upon rotation of the rotating bunch building device 34 when the machine is started with the bunch building mechanism in bunch building position, the edge portion 36 of the rotating device 34 will engage the spiral grooves in the worm and rotate the latter in a direction to progressively move the worm backward or out of bunch building relation with the bunch building device.

During main service windings it is desirable that the bunch building worm shall remain quiescent, and since it may contact with the side of the rotating device 34, which is herein shown as rotating with the main builder cam, means are provided to prevent rotative movement of the worm during regular traverse. Such means consists of a pin 37, in the present instance, which extends from the outer face portion 38 of the worm and bears upon the peripheral portion of the bunch building device 34 during main service windings, the result being that on commencement of the bunch building windings of a new set of bobbins, the worm 32 will engage the rotating device 34 in substantially the same place as the previous

bunch building windings, so that the windings of successive series of bobbins will be uniform.

The present invention contemplates that the bunch building worm 32 shall be moved to its bunch building position relative to the rotating bunch building device 34 by manual effort, and as one good practical form of means to this end, the builder arm has associated therewith treadle operating means for moving the worm into bunch building position.

More particularly, the bunch builder arm has a bracket 39 secured thereto and provided with a bearing 40 for a rock shaft 41, the other end portion of which is mounted in a bearing 42 extending conveniently from the bracket 27, and secured to the rock shaft 41 is a treadle 43 whereby under manual effort the machine attendant may actuate the rock shaft to operatively position the bunch building worm.

Mounted upon the rock shaft 41 and secured thereto by screw 50 is an arm 44, the lower end portion of which is turned at 45 and bears against a sliding pin 46 which may be mounted for sliding movement in a bearing 47 carried by the lower portion of the bracket 27 with the end 48 of the pin

resting against the face 49 of the worm 32, as more clearly shown by Fig. 3. From the construction described, it will be apparent that upon rocking movement being imparted to the rock shaft 41 by the machine attendant or machine operator, the pin 46 will be moved transversely of the builder arm to move the worm 32 on the pin or dead shaft 30 into its operative position below the rotating bunch building device 34 when the building arm is lowered.

In order that the bunches on a series of bobbins may all be of the same size, it is desirable that the worm be moved by the operator or machine attendant to the same operative position each time it is actuated or moved to operative relation with the rotating builder device 34. In the construction shown, the pin or dead shaft 30 which is threaded into the bracket 27, as shown, may be adjusted transversely of the builder arm by letting up on the nuts 31 and turning the pin in its threaded connection with the bracket 27, thereby moving the shouldered portion 30^a to different positions transversely of the builder arm in accordance with the bunch desired, such shouldered portion acting as a stop against which the inturned edge 33^a of the collar 33 rests when the worm is moved to operative position by the pin 46.

Thus by adjustment of the dead shaft 30, the size, as well as the uniformity of bunches on a successive series of bobbins, may be determined.

When a series of bobbins have been completely wound at the end of service traverse,

the machine attendant or operator lowers the ring rail or other yarn guides for dosing, and the ring rail is usually held in such lowered position by the customary catch, not shown. At this time, however, the weight 70 is acting upon the builder arm, still holds the follower 19 against the main builder cam, which at such time is not being rotated. An empty set of bobbins having been supplied to the machine, the attendant may then place his 75 foot upon the treadle 43 to thereby lower the builder arm, and when the side of the face of the worm positions below the rotating building device 34, the worm will be moved outwardly or into bunch building relation with 80 the rotating device and will be engaged thereby when the attendant removes his foot from the treadle. The machine is now ready to be started, and power being applied by the usual shipper mechanism, the first operation of the machine is to build the bunch, which is effected by direct engagement between the worm 32 and the rotating builder device 34 which progressively moves the worm away from and finally out of operative position, whereupon regular service traverse commences, and during such regular service traverse the worm 32 remains quiescent.

When passing from bunch building to 95 regular service traverse, there should be no "jump" of the yarn guides or ring rail and to gradually bring into operative relation the main builder cam and its follower 19 at the completion of the bunch, the worm 32 100 has its threaded surface formed as or merging into a scroll 52, so that as the rotating building device 34 moves the worm into its inoperative position, its edge portion 36 will travel along the scroll 52 until the builder arm gradually rises to bring the follower 19 against the main builder cam, and owing to the stop 37 extending from the face of the worm, the worm will remain non-operative 105 in fixed position until it is again moved to operative bunch building position, whereupon the same portion of the worm as was before engaged by the rotating building device will again come into play, thus insuring 110 uniformity in the size and location of the bunches on a succession or series of bobbins.

What is claimed is:

1. In a builder mechanism, the combination of a main builder cam, a builder arm, a bunch builder worm carried by the builder arm, operator operated means carried by the builder arm for moving the worm into bunch building position, a rotating bunch building device for engaging the worm and restraining it from movement out of bunch building position until such device is rotated and thereupon acting directly upon the worm to progressively move it out of bunch building position.

2. In a builder mechanism, the combina-

tion of a main builder cam, a builder arm, a bunch builder worm carried by the builder arm, treadle operated means carried by the builder arm for moving the worm to bunch building position, a rotating bunch building device for directly engaging the grooves of the worm and restraining it from movement out of bunch building position until the device is rotated and thereupon acting to turn the worm to progressively move it out of bunch building position.

3. In a builder mechanism, the combination of a main builder cam, a builder arm, a rotating bunch building device, a bunch building worm carried by the builder arm and directly engaging the rotating bunch building device to build the bunch and by which the worm is held in bunch building position, and manually operated means carried by the builder arm for moving the bunch building worm into operative position.

4. In a builder mechanism, the combination of a main builder cam, a builder arm, a rotating bunch building device of generally circular contour, a bunch building worm carried by the builder arm and directly engaging the bunch building device for bunch building purposes and held from movement out of bunch building position by said device until rotation thereof and thereupon being progressively moved out of bunch building position.

5. In a builder mechanism, the combination of a main builder cam, a builder arm, yarn guiding means connected to the builder arm, a rotating bunch building device, a bunch building worm carried by the builder arm and directly engaging the rotating device for bunch building purposes and by which engagement the worm is held in bunch building position until rotation of said device whereupon it is progressively moved out of bunch building relation thereto, and manual means on the builder arm for sliding the worm transversely of the builder arm into bunch building position.

6. In a builder mechanism, the combination of a main builder cam, a builder arm, a yarn guide connected to the builder arm, a worm carried by the builder arm and movable transversely thereto into and out of bunch building position, a bunch building device rotating coincidently with the main builder cam and having an edge portion to directly engage in the peripheral grooves of the worm for building the bunch and moving the worm out of bunch building position, and a treadle on the builder arm for moving the worm into bunch building position.

7. In a builder mechanism, the combination of a main builder cam, a builder arm, a yarn guide connected to the builder arm, a worm carried by the builder arm and movable transversely thereto into and out of

bunch building position, and having the worm grooves extending spirally about the axis of the worm, a bunch building device rotating coincidently with the main builder cam and having an edge portion to directly engage in the peripheral grooves of the worm for building the bunch and moving the worm out of bunch building position, and a treadle on the builder arm for moving the worm into bunch building position.

8. In a builder mechanism, the combination of a main builder cam, a builder arm, a yarn guide connected to the builder arm, a worm carried by the builder arm and movable transversely thereto into and out of bunch building position, a bunch building device rotating coincidently with the main builder cam and having an edge portion to directly engage in the peripheral grooves of the worm for building the bunch and moving the worm out of bunch building position, a stop to prevent rotation of the bunch building worm when out of bunch building position, and a treadle on the builder arm for moving the worm into bunch building position.

9. In a builder mechanism, the combination of a main builder cam, a builder arm, a bunch builder worm carried by the builder arm, operator operated means carried by the builder arm for moving the worm into bunch building position, a rotating bunch building device for engaging the worm and restraining it from movement out of bunch building position until the device is rotated and thereupon acting directly upon the worm to progressively move it out of bunch building position, and a stop to prevent rotation of the worm when out of bunch building position.

10. In a builder mechanism, the combination of a main builder cam, a builder arm, a worm mounted for sliding movement transversely of the builder arm, a bunch building device rotating with the main builder cam having an edge portion to directly engage the spiral threads of the worm to rotate it for moving the worm transversely of the builder arm out of bunch building position, and manually operated means on the builder arm for moving the worm into bunch building position.

11. In a builder mechanism, the combination of a main builder cam, a builder arm, a worm mounted for sliding movement transversely of the builder arm, a bunch building device rotating with the main builder cam having an edge portion to directly engage the spiral threads of the worm to rotate it for moving the worm transversely of the builder arm out of bunch building position, a pin on the builder arm for moving the worm into bunch building position, and a treadle for actuating the pin.

12. In a builder mechanism, the combination of a main builder cam, a builder arm,

and a bunch builder attachment, comprising, a device rotating with the main builder cam, a worm carried by the builder arm and movable transversely thereof into and out of engagement by the rotating device for building the bunch, and means for preventing rotating of the worm during regular traverse.

5 bunch building position, a rockshaft on the builder arm for manually moving the worm into bunch building position for direct en-

In testimony whereof, I have signed my name to this specification.

HORACE H. BURDETT.
